(57) **CLAIM**

The ornamental design for a thermal container, as shown and described.

DESCRIPTION

FIG. 1 is a front elevation view of a thermal container showing my new design.

FIG. 2 is a top plan view thereof.

FIG. 3 is a bottom plan view thereof.

FIG. 4 is a perspective view thereof.

FIG. 5 is a perspective view thereof with the handle in an upward position.

FIG. 6 is a perspective view thereof with the cover.

FIG. 7 is an exploded top perspective view thereof; and, FIG. 8 is an exploded bottom perspective view thereof.

The portions of the article shown in broken line form no part of the claimed design.
